(74) Attorney, Agent, or Firm—Smith-Hill and Bedell

(57) CLAIM

The ornamental design for “a central hub for a DVD box”, as shown and described.

DESCRIPTION

FIG. 1 is a perspective view of a central hub for a DVD box showing my new design;

FIG. 2 is a top plan view in a fully opened position; and, FIG. 3 is a bottom plan view of FIG. 2.

The broken lines showing the remainder of the DVD box is for illustrative purposes only and forms no part of the claimed design.
